UNITED STATES PATENT OFFICE.

ABRAHAM L. POSTMAN, OF BROOKLYN, NEW YORK.

METHOD OF MAKING SHOES.

Application filed November 19, 1925. Serial No. 69,977.

This invention relates to shoes in general and particularly to the process of producing same.

One of the prime objects of this invention 5 is a novel, highly efficient and inexpensive method of producing shoes without the necessity of turning the upper.

Another object of this invention is the effective method of attaching to the upper 10 the sole of a shoe by means of transverse sewing, i. e. in such a way that the stitches are disposed in transverse direction to the thickness of the sole.

Another object of my invention is to provide 15 a temporary insole used in my process by means of which the upper may be temporarily attached to the last for such a time as is necessary to shape the upper to the contour of the last.

Another object of my invention is the 20 finished product produced by my process.

The foregoing and further objects will be more fully apparent from the following description and the accompanying drawings, 25 forming part of this disclosure, and in which:—

Figure 1 represents a cross-section through my temporary insole,

Figure 2 is a partial top view of a last to 30 which my temporary insole is temporarily attached,

Figure 3 is a side elevation of the last showing the insole attached,

Figure 4 is a partial top view of a last to 35 which is attached a temporary insole and an upper,

Figure 5 is a cross-sectional view taken on line 5—5 through Figure 4,

Figure 6 is a cross-sectional view through 40 the upper, the temporary insole and the sole attached to the upper,

Figure 7 shows a similar cross-sectional view to that of Figure 6 with the temporary insole removed,

Figure 8 illustrates the temporary insole 45 removed after it has served its purpose,

Figure 9 is a cross-sectional view through the finished shoe having a sock lining inserted, covering the line of attachment between the upper and the sole,

Figure 10 illustrates a staple used for temporarily attaching the temporary insole to the upper before attaching the sole,

Figure 11 illustrates the same staple in

its form, while holding the temporary insole and the upper together.

Before commencing the specific description of my method I deem it essential for the purpose of comparison to enumerate a few heretofore used methods of producing 60 shoes.

The old way of shaping the upper on a last and then inverting it after the sole has been attached is one of the principal ways used up to now. The turning of the 65 upper has marked disadvantages which are well-known and need no explanation. To overcome these disadvantages many other methods have been employed which are known under various names and produce 70 more or less cumbersome shoes without reducing materially the cost of manufacture. In most cases these methods achieve bulky, uncomfortable footwear because of additional means inserted to accomplish the result sought.

As will be evident from the following description my method is not only new but most efficient and inexpensive, and produces an article which is not only comfortable to 80 wear, but durable in its use.

My process consists principally in eliminating the heretofore used permanently attached insole and I shall in a general way describe the manner in which I produce 85 shoes.

Referring to the drawings numeral 10 denotes a stiff and tough sheet of the outline of the sole. At its periphery there is provided a flexible strip 11 which is preferably 90 sewed to the sheet in such a way as to provide a firm connection between the sheet and the strip at one edge of the latter, while its other or inner edge is free. This insole comprises the subject matter of my copending application Ser. No. 92,173, filed March 4, 1926.

In Figures 2 and 3 will be seen a last 12 to which my temporary insole is temporarily attached by means of nails 13. The upper 100 of the shoe shown in Figures 4 and 5 and indicated at 14 is provided with a "doubler" 14' and is attached with the "doubler" fac-

ing the last 12 so as to overlap with its edge the strip 11 of the temporary insole.

As will be seen from Figures 2 and 5 the contour of the temporary insole coincides with the shape of the last but is considerably

smaller in dimension. Due to this fact it is possible to temporarily attach the upper by means of nails 15 to the last without touching the temporary insole. In other words, the upper is temporarily attached on a line beyond the periphery of that temporary insole. The turned over edges of the upper overlap the inverted edge of strip 11 of the temporary insole. Now the strip 11 and 10 the edge of the upper together with the "doubler" is temporarily stapled from underneath the strip 11 and in outward direction. This stapling is done in such a way that in the spaces between nails 15 a staple indicated at 16 is passed through the material of strip 11 and the edge of the upper. In this way the upper is now secured to the last and is shaped to the latter's form in the ordinary well-known way. The upper 20 is permitted to set. Hereafter the nails holding down the temporary insole and the periphery nails holding down the upper are removed and the last is extracted from the now permanently shaped upper.

25 A shoe sole 17 is prepared by slitting or channeling its edge at a slant. The slit portion is bent up as shown in broken lines in Figure 6 at 18 and the sole is now attached by means of vertical sewing to the upper as indicated at 19.

I particularly point out the fact that the sewing is done substantially at right angles to the thickness of the sole because of the importance of this feature. When the shoe 35 is worn and the sole thinned down due to wear until the stitches 19 touch the ground, these stitches will wear down evenly together with the sole and form so to speak rivets which will securely hold the sole together 40 with the upper until the sole is worn out. After sewing the sole to the upper and turning the flap 18 of the sole to its original position as shown in Figure 7, the temporary insole 10 is removed and with the temporary insole also the staples are withdrawn 45 from the upper. The temporary insole is shown in Figure 8 as it looks after its withdrawal from the shoe and showing at 16 the disconnected staples. The finished 50 product is shown in cross section in Figure 9 which comprises the upper 14, the "doubler" 14', the sole 17 stitched together at 19 with the upper and a sock lining 20 which is overlapping the attached edge of the upper 55 and the stitched portion where the sole is attached to the upper.

From the foregoing it will be evident that my method eliminates the turning of the upper and it also eliminates a cumbersome 60 insole which is attached usually to the upper and which causes discomfort to the wearer aside from the fact that it is costly. My method also eliminates the application of paddings or heavy insoles necessary to 65 cover the unusually highly protruding

stitches caused by the employment of a permanent insole or a welt employed heretofore. The product of my method is a light, durable, simple, inexpensive and most comfortable footwear in which the upper 70 is directly attached to the sole and where an insole or welt sewed to the upper is entirely eliminated.

While I have described my method and while I have specified certain means employed in my method, I shall not be limited to its exact wording or showing, and I therefore reserve the right to make such changes and improvements within the scope of my invention as will become necessary to still 80 further increase the efficiency and decrease the cost of production.

I claim:—

1. The process of producing shoes and the like, which comprises attaching a temporary insole provided with a peripheral strip, to a last, attaching an upper to the last so that its edge overlaps the edge of said temporary insole, stapling the strip of the insole together with the edge of said upper, permitting the upper to set and shape itself to the form of the last, removing the means of attachment holding the temporary insole and upper to the last, removing the last, sewing a sole to the upper and removing the temporary insole.

2. The process of producing shoes and the like, which comprises, attaching to a last a temporary insole provided with a peripheral attaching strip, temporarily attaching 100 an upper to the last, for the purpose of shaping and setting it, in such a way that the attached edge of the upper overlaps the edge of said temporary insole, temporarily stapling the edge of the upper to the strip of the temporary insole, permitting the upper to set, detaching the temporary insole and the upper from the last, removing the last, sewing a sole to the upper at a line located beyond the outer edge of said temporary insole, 110 and removing the latter and the staples which held the upper and the temporary insole together.

3. The process of producing shoes and the like, which comprises, attaching to a last a temporary insole having a peripheral attaching strip, temporarily attaching to the last an upper so that its edge overlaps the attaching strip of the temporary insole, the points of temporary attachment of said upper being located beyond the periphery of said temporary insole, stapling together the overlapping edge of said upper and the attaching strip of said temporary insole at points lying between the points of temporary attachment of said upper, permitting the upper to set on the last, removing the means of attachment holding the temporary insole and the upper to the last, removing the last, slitting the outer edge of a sole and sewing 130

it to the upper in perpendicular direction and at a line located outside the periphery of said temporary insole, and detaching the latter together with the staples from said upper.

4. The process of producing shoes and the like, which comprises temporarily attaching to a last a temporary insole provided with an attaching strip, temporarily attaching to the last at a line located beyond the periphery of said temporary insole an upper, provided with a lining, so that the edge of said upper overlaps the attaching strip of said temporary insole, stapling together the edge of said upper and the attaching strip of said temporary insole at points disposed between

the points of temporary attachment of said upper, said stapling being done from under the attaching strip of said temporary insole and in outward direction, permitting the upper to set and take the shape of the last, detaching from the last the temporary insole and the upper and removing the last, slitting the edge of a sole and sewing it to the upper and lining at a line beyond the periphery of said temporary insole, and in perpendicular direction to the sole, and removing the temporary insole together with the staples from within the shoe.

Signed at New York, in the county of New York and State of New York.

ABRAHAM L. POSTMAN.
